Baldwin Wright

UNITED STATES PATENT OFFICE.

GUSTAVE O. DEGENER, OF HARTFORD, CONNECTICUT, ASSIGNOR TO ROYAL TYPEWRITER COMPANY, INC., OF NEW YORK, N. Y., A CORPORATION OF NEW YORK.

TYPEWRITING MACHINE.

Application filed January 9, 1924. Serial No. 685,237.

To all whom it may concern:

Be it known that I, GUSTAVE O. DEGENER, a citizen of the United States, residing at Hartford, in the county of Hartford and 5 State of Connecticut, have invented certain new and useful Improvements in Typewriting Machines, of which the following is a specification.

This invention relates to the paper feeding and guiding mechanism of typewriting machines. In the Royal Standard machine as heretofore marketed the paper is fed under the platen and held in yielding contact therewith by a group of rolls mounted in 10 frames which can be adjusted to withdraw the rolls from the platen when it is desired to arrange the paper on the platen. These combined feeding, guiding and pressure rolls cooperate with pressure rolls 15 which normally hold the paper after passing around the front of the platen with yielding pressure on the upper portion of the platen. Means has heretofore been provided, and as shown in prior patents issued to the Royal Typewriter Company, Inc., for so mounting these upper pressure and guide rolls that they may be moved from their normal or working position to a position above and in rear of the platen 20 and in rear of the paper table, or to a position a short distance above the platen, and in such mechanism as heretofore used, provision has also been made for withdrawing the lower rolls from the platen and simultaneously elevating the upper rolls.

The principal feature of my present invention consists in so mounting the upper pressure rolls of a typewriting machine that they may be moved from their normal position on top of the platen to a position a considerable distance in front thereof so as to leave a clear space between the pressure rolls and the platen for the adjustment of the paper. This feature of the mechanism, 40 which so far as I am aware is broadly new, is preferably combined in a novel way with the valuable features of the paper feeding and guiding mechanism above mentioned and found in the Royal Standard machine 45 as at present marketed.

In the accompanying drawings:—

Figure 1 shows a side elevation of such parts of a typewriting machine of the Royal type to which my improvements are applied 55 as is necessary to indicate the preferred em-

bodiment of my invention. In this figure of the drawing the normal or working position of the upper pressure rolls is shown by full lines and certain adjusted positions of such pressure rolls are indicated by dotted lines.

Figure 2 is a side elevation of one of the side arms of the frame of the upper pressure rolls and indicates how said frame is pivotally connected with the carriage. In 65 Figure 2 the upper pressure rolls are shown in one of the positions which they occupy when raised a short distance above the platen.

Figure 3 is a view similar to Figure 2 70 showing the upper pressure rolls raised to a greater extent.

Figure 4 is a plan view of the upper pressure rolls, their frame and certain parts connected therewith.

Figure 5 is a perspective view of a latch forming part of the mechanism.

Parts of a typewriter carriage are indicated at A, and B indicates a platen. C indicates a shift rail for the carriage of the kind found in all Royal Standard machines. The lower rolls for guiding and feeding the paper and pressing it against the under side of the platen are indicated at D and E indicates the gearing between parts of the roll shifting mechanism and a lever F by means of which the rolls are adjusted. By operating this lever the rolls may be moved into and out of engagement with the under side of the platen.

The upper pressure rolls g' are mounted to turn about and to be adjusted longitudinally on a cross bar g to the opposite ends of which are secured the front ends of side bars H which are pivotally mounted at their rear ends in the manner soon to be described. The rear portions of the side bars H are pivotally connected at j to the upper free ends of the arms J of a cross bar K. The lower ends of the arms J are pivotally connected at k to the side plates of the carriage. The cross bar K and its arms J constitute a rocking frame to which the side bars H of the roller carrying frame are connected and these side bars with the front cross bar g constitute what is termed in this art a "bail" which supports the upper pressure rolls. This roll carrying frame or bail is movable about an axis in rear of the platen and is also movable fore and 105

aft of the machine so that the front pressure rolls may be lifted away from the platen and moved to a position above and in rear of the platen or they may be moved 5 forwards away from the platen to a position a considerable distance therefrom. Each side bar H of the bail or roll carrying frame is preferably given the form shown in the drawing. It has a front 10 straight part h and a curved rear part h', being bifurcated or recessed at h² in rear of its pivotal connection with the associated arm J. This construction produces an arm h³ formed on its rear curved edge with 15 two recesses or notches x and y. Each bar H is also formed with a lug h⁴ for a purpose hereinafter described. A knob or handle H' is provided for moving the bail or roll carrying frame to its adjusted positions. 20 A horizontally arranged spring L connects one end of the frame bar K with the carriage frame and tends to hold the bail in the normal position shown in full lines in Fig. 1. Vertically arranged springs M (two 25 being preferably employed), connect the frame bar K with the carriage frame in the manner also indicated in Figure 1. When the parts are in the position shown in Figure 1, the springs M hold the bail in 30 normal position against accidental displacement and they also cause the rolls g' to press on the platen. It will be observed that at this time the rear end h⁵ of the side bar H bears on a roller or locking device R 35 mounted on the carriage frame and the springs M which at this time operate in rear of the pivot of the arm J pull the bail downwards, the roller R acting as a fulcrum. In this way the rollers g' are held with yielding 40 pressure on the platen. The spring L tends to retract the bail and also assists in holding the rolls g' with a yielding pressure on the platen. The springs M are more powerful than the spring L, but they co- 45 operate to hold the rolls g' on the platen when the parts are in the position shown in Figure 1.

The bail is so mounted that it may be held 50 yieldingly in various positions as before described and may be moved upwardly and rearwardly to a position above the platen or to a position in rear thereof as indicated by dotted lines at X, Figure 1. The mounting is also such that the bail may be 55 moved horizontally fore and aft of the machine in such manner as to hold the upper pressure rolls g' a considerable distance in front of the platen as indicated by dotted lines at Y, Fig. 1. This is a new feature in 60 typewriting machines so far as I am aware and it affords a clear space between the upper pressure rolls and the platen for adjustment of the paper. When the rolls g' are 65 in the dotted line position shown at Y, Fig. 1, the paper may be disposed as indicated

by dotted lines at P. When the rolls g' are moved back to normal position, the paper is moved rearwardly to the position shown at P' and is held in close contact with the upper side of the platen. These operations 70 may be performed by taking hold of the knob or handle H' and giving proper movements to the bail, or the bail may be moved from its normal or retracted position to an elevated position by means of the lever F 75 which adjusts the lower feed rolls D. For this purpose one of the side bars H carries a latch N which is pivotally connected to the lug h⁴ and is formed with an arm n extending across the top of the associated 80 arm H and with an arm n' having an inclined front edge n² and a straight rear edge n³. When the parts are in the position shown in Figure 1 by full lines and the lever F is moved forward to release the lower 85 pressure rolls. Said lever engages the latch N and moves the bail forward until the rolls g' assume the position shown at Y. Should the lever F become accidentally displaced, it may be returned to normal position without moving the bail, as the lever will move 90 outwards on the incline n² of the latch. The arm n normally holds the latch in the position shown in Figure 1. By lifting the latch or turning it on its pivot, it may be moved 95 out of the path of the lever F so that the latter may be operated to adjust the lower pressure rolls without moving the bail. It will be observed that the lever F as usual is 100 slightly bent so that its upper part is not adapted to engage the latch while its middle portion engages the latch when operated for that purpose.

When the bail is in normal or working position the lower end of the arm h³ of each side bar H rests on the roller R as shown, and the springs L and M hold the rolls g' with a yielding pressure on the platen. When the bail is moved to the position shown in Figure 2, the rollers R engage the notches y and the bail is yieldingly held in the position shown in Figure 2. When the bail is raised in the manner indicated in Figure 3 the ends of the arms h³ of the side bars engage stops s on the arms J and when the bail is lifted to the extent shown at X, Figure 1, the rollers R engage the recesses x in the side bars of the bail. It will be observed that the springs M which are connected at their lower ends to the carriage frame and at their upper ends to the cross bar K above the pivotal connections k of the arm J with the frame are so disposed that the upper ends of the spring cross the pivots k when the bail is moved from one position to another and thus the springs M tend to hold the bail in the position to which it is adjusted and being more powerful than the spring L prevent the return of the bail to normal position after being shifted to 110 115 120 125 130

the position indicated at Y. When the bail is shifted to the position Y, the lugs h^4 rest on the machine frame as indicated and hold the bail at the proper elevation.

5 When the bail is moved upwardly to the position shown in Figure 2, the rollers R enter the notches y and the spring M and L tend to hold the bail in the position to which it is set. When the bail is moved 10 from the position shown in Fig. 2 to that shown in Fig. 3 or to that shown in Fig. 1 by dotted lines at X, the rollers R ride along the curved rear edges of the side bars H. The springs M and L press the side 15 bars against the rollers, thus enabling the bail to be raised steadily and smoothly from one position to another.

While my improvements are designed especially for use in connection with visible 20 front strike machines of the Royal type, they may be embodied so far as the broader features of my invention are concerned, in machines of other kinds.

I claim as my invention:

15 1. In a typewriting machine a pressure roll and a frame therefor movable about an axis in rear of the platen to lift the roll to a position above the platen and movable also fore and aft of the machine to shift the pressure roll to a position in front of the platen and a considerable distance therefrom.

2. In a typewriting machine a pressure roll and a frame therefor pivotally mounted 35 in rear of the platen and movable bodily fore and aft of the platen.

3. In a typewriting machine a pressure roll and a frame therefor associated with a rocking frame in rear of the platen with 40 which it is pivotally connected, said rocking frame being movable fore and aft of the machine about an axis in rear of the platen whereby the pressure roll is moved horizontally towards and from the platen.

45 4. In a typewriting machine a pressure roll and a frame therefor associated with a rocking frame in rear of the platen with which it is pivotally connected, and means for holding the roll carrying frame in an elevated position above the platen.

50 5. In a typewriting machine a pressure roll and a frame therefor associated with a rocking frame in rear of the platen with which it is pivotally connected, and means 55 for holding the roll away from the platen in its elevated positions above the platen.

60 6. In a typewriting machine a pressure roll and a frame therefor associated with a rocking frame in rear of the platen with 65 which it is pivotally connected, means for yieldingly holding the frame in retracted or working position, and means for elevating the frame away from the platen and for moving it fore and aft of the machine.

65 7. In a typewriting machine an upper

pressure roll and a frame therefor mounted to swing vertically and to move fore and aft of the machine, lower pressure rolls adapted to bear on the under side of the platen, means for moving the lower pressure rolls into and out of engagement with the platen, and devices operating when the lower rolls are being withdrawn from the platen for moving the upper pressure roll fore and aft of the machine to a considerable 70 distance in front of the platen.

8. In a typewriting machine an upper pressure roll and a frame therefor movable to swing vertically and to move fore and aft of the machine, lower pressure rolls 80 adapted to bear on the under side of the platen, an actuating lever operatively connected with the lower pressure rolls for moving them into and out of contact with the platen, and connections between said lever and the frame of the upper pressure rolls for moving said upper rolls fore and aft of the machine when said lever is operated to adjust the lower rolls.

9. In a typewriting machine an upper pressure roll adapted to bear on the upper portion of the platen, a frame in which said roll is mounted comprising a front cross piece and side pieces having curved rear portions formed with notches, a rocking frame with which the side pieces are connected and a holding device adapted to enter said notches when the roll carrying frame is raised to different positions.

10. In a typewriting machine an upper pressure roll, a horizontally arranged frame in which it is mounted, a rocking frame pivotally connected with the machine frame and pivotally connected with the roll carrying frame, springs arranged vertically and horizontally connected with the machine frame, and with the rocking frame for holding the pressure roll in engagement with the platen and in different adjusted positions when raised from the platen and for 100 also holding the frame when moved horizontally forwards to shift the pressure roll to a position in front of the platen.

11. In a typewriting machine the combination with the platen and its carriage, of pressure rolls adapted to bear on the upper portion of the platen, a frame in which said rolls are mounted, and rocking connections between the roll carrying frame and the carriage frame by which the roll carrying frame is moved bodily fore and aft of the machine.

12. In a typewriting machine, embodying the usual paper feed rolls, and means for releasing the same, the combination of an upper pressure roll, a mounting therefor permitting the same to move to a position in front of the platen and at a considerable distance therefrom to afford a clear space 125 for the adjustment of the paper, and means 130

whereby the movement of said release means will move the upper roll to said forward position.

13. In a typwriting machine embodying 5 the usual paper feed rolls and means for releasing the same, the combination of an upper pressure roll, a mounting therefor permitting the same to move to a position in front of the platen and at a considerable 10 distance therefrom to afford a clear space

for the adjustment of the paper, means whereby the movement of said release means will move the upper roll to said forward position, and means for enabling the release means to be moved without moving 15 the upper roll.

In testimony whereof, I have hereunto subscribed my name.

GUSTAVE O. DEGENER.
